UNITED STATES PATENT OFFICE

ALFRED T. PRENTICE, OF VALPARAISO, INDIANA

INTERNAL COMBUSTION ENGINE

Application filed April 21, 1930. Serial No. 445,877.

My invention relates to improvements in internal combustion engines and it more especially consists of the features pointed out in the claims.

5 The purpose of my invention is to provide a novel engine construction in which the piston and cylinder both move toward and away from each other, that connects the piston to a crank opposite to that which reciprocates the cylinder; that utilizes any desired form of 10 valve control; that operates on the Diesel, or self ignition principle; that for a given weight produces a large increase in power over that supplied by an ordinary internal 15 combustion engine in which only the piston is in motion and the cylinder is stationary; that because of the simultaneous movement of the piston and cylinder the engine does not become heated, in consequence the usual heat 20 losses are eliminated and a water jacket for cooling purposes is not required; and furthermore the usual ignition system is also eliminated.

With these and other ends in view, I illustrate in the accompanying drawings such instances of adaptation as will disclose the broad underlying features of the invention without limiting myself to the specific details shown thereon and described herein.

30 Figure 1 is an elevation in section of an assembled engine showing the piston and cylinder in firing position.

Fig. 2 is a top plan view in section on line 2-2 of Fig. 1.

35 Fig. 3 is an elevation in section showing the piston and cylinder separated.

Fig. 4 is a detached elevation of a packing ring guide.

40 Fig. 5 is a detached sectional view showing the cylinder receiving a fuel charge.

Fig. 6 is a detached sectional view showing the ignition chamber opposite the fuel inlet.

In practicing my invention I may use whatever alternatives or equivalents of structure 45 that the exigencies of variable conditions may demand without departing from the broad spirit of my invention.

The outstanding feature of my reaction motor resides in the use of a crank shaft, to 50 which a sliding cylinder is attached by a

pair of connecting rods and to which a piston connecting rod is also attached in opposition, so that at the detonation of the compressed charge the piston and cylinder head move in opposite directions away from each other.

55 Any desired type of casing may be used. It may provide for precompression or any cooperating modifications. As instanced in the drawings, a simple form is shown at 1. It may comprise a removable head 2 and a separable crank casing 3. Between the main casing 1 and the bottom or crank case 3, a crank shaft 4 is rotatable in bearings 6. The casing 1 may have endwise projections 5. At its upper end it is enlarged in diameter to accommodate a sleeve valve which has an endwise movement to control the admission of fuel etc. It has a head 18 and a cylindrical projection 19. This forms a sleeve in which there is an annular ignition chamber 17. An 60 opening 20 leads into the chamber 17. It registers with the passageway 21 formed in the casing 1 when the sleeve is in its lowered position. At that time the head 12 of the cylinder 11 will in its up stroke have passed above the charging chamber 17 of the sleeve 18-19, so that when the port 20 is in line with the passageway 21 the charging chamber 65 will be sealed off by the wall of the cylinder 11.

70 The sleeve 18-19 may be actuated by a link 23 connected to a rocker arm 24, which in turn is moved by a rod 25, and it in turn is actuated by a cam 27 against a compression spring 26. The cam 27 is driven by gears 28 and the crank shaft 4. The ratio of the gears and the shape of the cam 27 may be varied as desired. Directly beneath the head 12 of the reciprocating cylinder 11 ports 16 are 75 formed. These, when the cylinder is in its lowest or firing position, are opposite the wall of the casing 1.

80 The piston 9 is attached to the crank 7 by connecting rod 10, and the cranks 8 are connected to the ears 14 of the cylinder 11 by means of connecting rods 13 attached to pins 15. A fuel chamber 22 is controlled by a rod 29 actuated from the crank shaft in any desired manner and sequence as, for instance, by a cam 30 and gears 38. The fuel inlets 85 90 95 100

and exhaust outlet are shown in Figs. 1, 3 and 5. Sealing-off rings of any well known type are placed above and below the opening 20 on the outside of the sleeve 19, and 5 similar sealing-off rings are placed on the inner wall of the sleeve 19 above and below the ignition chamber 17. Similarly the outer surface of the cylinder 11 is also sealed-off by rings positioned above and below the ports 16. Between the inner surface of the cylinder and the outer surface of the piston the usual 10 piston rings are placed.

In the position shown in Fig. 1, the cylinder is in its lowest position and the piston is 15 in its highest position leaving a space between for the firing charge which at this point is detonated by the heat of compression. The cylinder head 12 and the piston 9 move away from each other, thus securing a marked increase 20 in power without incurring the usual heat losses.

The rocker arm 24 may have a slot 31 at its fulcrum 32, which may be adjustable so as to vary the movement of the sleeve link 23. I may actuate the fuel control of the chamber 22 in any desired manner by means of a lever 33 connected to the stem 29. A cam 30 is driven by gears 38 and the crank shaft 4. This raises and lowers the stem 29 in co-operation with a spring 39. An exhaust port 37, when the cylinder is in its highest position communicates with the exhaust outlet 36 formed in the casing 1. In order that the sealing-off rings of the cylinder 11 do not 30 slip into the ignition chamber 17 I may form "bridges" 34, shown on Fig. 4, openings 35 are formed behind the bridges so as to preserve communication all around the ignition chamber 17.

40 The cycle of operation is quite simple. Under the pressure produced by the explosion fired by the heat of compression the cylinder head 12 moves up and the piston moves downward. At the end of such movement the exhaust port 37 of the cylinder comes into line with the port 36 thus freeing the power space from the carbon monoxide. The cylinder now starts downward as the piston starts upward. The first movement 45 downward of the cylinder closes the exhaust port 37 and the inlet ports 16 are opposite the ignition chamber 17. This has just previously, while in its lowered position received a charge of fuel through the openings 50 20 and 21 but now being in its raised position the passageway 21 is sealed off and the "charge" enters the cylinder to be compressed for the next detonation, after which the cycle 55 is repeated.

60 It has been shown by careful experiments that the piston of an internal combustion engine does not become heated due to its rapid motion which, the faster it moves, becomes more and more cool. The explosive charge is, by reason of the cylinder and piston

being connected to opposite positions on the crank shaft, expanded in two directions. If desired, I may combine any cooperating form of pre-heater in connection with the casing and the cylinder. I do not limit myself to the use of a sleeve valve as any well known form of poppet valve may be used instead. In such an event the casing head 2 would be closed tightly and the space between the cylinder head 12 and the head 2 used for preliminary compression in which case suitable ports leading to the ignition chamber may be provided.

70 As this reacting engine is of commanding importance, it is claimed in its broadest scope without being limited to any specific form of cooperating valves, ports, etc.

75 What I claim is:

1. A reacting engine, comprising a shaft 80 having a plurality of cranks thereon in opposite relation to each other, a casing having bearings for the shaft, a cylinder having a closed end slidable in the casing, a piston slidable within the cylinder below the closed end, connections from the cylinder and the piston to opposite portions of the crank shaft, and cooperating means comprising a slidable sleeve outside of the reciprocating cylinder for detonating a fuel charge between the piston and the cylinder head when these are 85 nearest to each other the detonation occurring through the heat of compression of the fuel, said sleeve having a closed end and movable adjacent the closed end of the cylinder.

90 2. In a reaction engine, a reciprocating cylinder, a casing therearound, a slidable sleeve between the casing and the cylinder, a reciprocating piston within the cylinder, a crank shaft, a pair of connecting rods from the cylinder to one side of the crank shaft, and a connecting rod from the piston to the opposite side of the crank shaft.

95 3. A reacting engine, comprising a casing, a shaft in the casing, a plurality of oppositely positioned cranks formed on the shaft, a closed head to the casing, a cylinder having a closed head slidable in the casing with its head in opposition to the head in the casing, a piston slidable within the cylinder, a closed 100 end sleeve between the cylinder and the casing and movable adjacent to and enclosing the cylinder head, connecting means from the cylinder and piston to oppositely positioned cranks of the crank shaft said means comprising a pair of connecting rods for the cylinder and a single connecting rod for the piston, and means for explosively moving the piston and the cylinder head away from each 105 other.

110 4. In a reaction engine, a casing having a cylindrical chamber open at one end and closed at the other, a tubular cylinder open 115 at one end closed at the other slidable in 120

the casing, cooperating means comprising a closed ended valve enclosing the closed end of the cylinder and movable between the casing and the cylinder, a piston slideable in the tubular cylinder, and means for imparting reciprocating motion to the piston and cylinder in opposite directions at recurring periods without recourse to water cooling.

In testimony whereof I affix my signature.
